MEANS FOR INTERCHANGEABLY MOUNTING STONES IN JEWELRY PIECES

Walter H. Bodnar, Washington, D. C.

Application February 1, 1952, Serial No. 269,491

3 Claims. (Cl. 63—29)

1

The present invention relates to the means of interchangeably mounting and supporting various stones in jewelry pieces such as rings, bracelets, etc.

The main object of the present invention is the provision to maintain and support a stone in a set condition relative to a jewelry piece.

Another object of the present invention is the provision of a suitable means for maintaining a jewelry stone in a rigid set condition with relation to a jewelry piece, which means can be quickly disengaged for the purpose of readily removing a stone and substituting another one in its place.

A still further object of the present invention is the provision of a jewelry stone, translucent or transparent in its nature, to receive at its back a paper sheet of various colors. The color showing through the stone would impart to the stone the color of the paper in the back of it, thereby simulating the natural color of a given genuine stone.

Another object of the present invention is the provision of a suitable means whereby both the stone and the color material in the back of it could be rigidly maintained in position within a jewelry piece.

With the above general objects in view and others that will appear as the invention is better understood, the same consists in the novel construction, combination and arrangement of parts hereinafter more fully described, illustrated in the accompanying drawing and pointed out in the appended claims.

In the drawing forming a part of this application and in which like designating characters refer to corresponding parts throughout the several views;

Fig. 1 is a cross sectional view, longitudinally through a jewelry piece, such as a bracelet, with the stone in elevation, showing the means for maintaining the stone in a rigid mounted condition with relation to the jewelry piece;

Fig. 2 is a perspective view of the jewelry piece and the stone in position therein, looking from the reverse side of the piece, also showing a modified form of the interengaging means of the stone with the jewelry piece.

Fig. 3 is a cross sectional view through the jewelry piece and the stone, with the stone maintaining means in elevation, the view having been taken on line 3—3 of Fig. 2;

Fig. 4 is a cross section on line 4—4 of Fig. 2;

Fig. 5 is a cross section through a stone and its mounting frame;

Fig. 6 is a similar view with a frame of a modified construction;

2

Fig. 7 is a cross section of a stone of a modified construction, without a frame; and

Fig. 8 is a perspective elevational view of a spring member used in connection with the jewelry piece for maintaining the stone in a rigid set position therewith.

Referring in detail to the present drawing there is shown therein jewelry piece 10, in this instance a bracelet. Centrally thereof the jewelry piece 10 has a raised portion or bulge 11, which extends outwardly from the body of the piece and is provided with opening 12. In a spaced relation with the rim portion of said bulge 11, and on a plane which is substantially a continuation plane of the body portion of the jewelry piece, the latter is provided with a pair of opposed tongues 13, which are in a longitudinal co-axial relation with the body of said jewelry piece 10.

Co-acting with said tongues 13, for maintaining in a set rigid position of stone piece 14, is an oblong spring 15, which is best shown in Fig. 8. Said spring 15 includes a central bulging arcuate portion and the ends which are on a common plane.

Referring now to the stone construction, the same is best illustrated in Figs. 5, 6 and 7, which are cross sections of stones either of various constructions or of various frames within which the stones are mounted. Thus, in Fig. 5 stone 14 has a mounting frame, which includes base 16. Extending from said base 16 from one face thereof is a stone engaging flange 17 corresponding in contour to the contour of a given stone. To maintain said frame in a rigid engagement with the stone flange 17 is spinned over the tapering side portion of the stone and adjacent the bottom thereof, as is best seen in Figs. 5 and 6. It is further observed that said flange 17 is in a spaced relation with the marginal rim of said base 16. 40 Flange 17 in its contour further corresponds to the contour of opening 12 and completely fills the same, with the bezel of the stone extending above the plane of jewelry piece 10, as is seen in Figs. 1, 3 and 4. The rim portion of base 16 outwardly of said flange 17 engages and contacts the inner face of the marginal portion of bulge 11 which is adjacent said opening 12.

From the hereinabove description it will therefore be seen that when the stone is in a position within said opening 12, all that needs to be done in order to maintain the stone in a rigid interlocked position relative to the jewelry piece, is to insert spring 15 with its ends engaging said tongues 13, and disposed between the latter and the marginal portion of said bulge 11 adjacent opening 12, as is clearly seen in Figs. 1 and 3.

The central arcuate portion of said spring 15, pressing at base 16 will maintain the frame with the stone in an operative position with the jewelry piece. In order to change the stone, all that is required is to give an angular shift to spring 12 in order to disengage the same from tongues 13. This will condition the jewelry piece to receive in substitution another stone either of a different color or of a different cut.

The modified stone mounting frame, shown in Fig. 6, is of a construction similar to that illustrated in Fig. 5, except that in the former base 16 is provided with opening 18. Insertion of various colored papers within said opening 18 will cause the color of a given paper to show through the stone, if the stone is translucent or transparent. Paper piece 19, positioned within said opening 18, as shown in Fig. 3, will be maintained in its operative position along with the stone mounting frame and the stone, by the action of spring 15, the latter bearing by its central portion directly against said paper piece 19.

As a modification of the construction of tongues 13, illustrated in Figs. 2, 3 and 4, the free ends of said tongues 13 are provided with a pair of spaced lugs 20 upwardly extending from said tongues 13. The pair of said lugs 20 in each tongue 13 defines a slot wherein the end of spring 15 is receivable. By virtue of this arrangement it will be impossible for spring 15 to accidentally shift in a lateral direction to be displaced. Said lugs 20 prevent such an occurrence. In order to disengage spring 15 from the assembly and remove the same preparatory to the substitution of one stone for another, at least one end of spring 15 must be raised above the free ends of said lugs 20 in one tongue 13 so that the raised end of the spring may be laterally shifted past said one tongue 13. When this has been done the removal of the spring is assured.

In Fig. 7 there is shown another modification of the construction of stone 14. Instead of having a metallic base 16 or flange 17 the stone itself is provided with horizontally extending flange 21 on the plane of its base. Said flange 21 is capable of engaging the marginal portion of bulge 11 from the bottom thereof, the same as the mounting frame shown in Figs. 5 and 6.

It is further observed that said tongues 13 may be either stamped out from the body of a jewelry piece, or they may be soldered thereto or in any other manner affixed thereto.

From the hereinabove description it will be seen that stones 14 of various colors as well as variously colored paper inserts 19 may be interchangeable in the same jewelry piece such as ring, bracelet, etc. The desirability of interchanging various stones in the same jewelry piece may be particularly in vogue in connection with costume jewelry. The facility of changing variously colored semi-precious stones will be appealing for economical reasons, because the wearer needs only to supply herself or himself with a number of variously colored stones, which can be used interchangeably in connection with only one jewelry piece. A stone made even of ordinary glass will give quite a good simu-

lation of variously colored semi-precious stones when variously colored paper inserts such as 19 are at the back thereof.

When lugs 20 are used in connection with tongues 13 it is of course necessary that spring 15 should be shorter than the width of bulge 11, so that said spring can expand and longitudinally shift, when stone 14 is manually depressed against said spring 15 preparatory to manually raising one end of said spring 15 so as to elevate the latter above lugs 20 in order to withdraw the spring from its operative position.

While there is described herein a preferred embodiment of the present invention, it is nevertheless to be understood that minor changes may be made therein without departing from the spirit and scope of the invention as claimed.

What I claim as new is:

1. In a jewelry piece, a body portion, an offset bulge extending from one face of said body portion, said bulge being provided with an opening therethrough, a stone assembly including a stone of a contour corresponding to the contour of said opening and a mounting frame within which said stone is receivable and rigidly engageable, said mounting frame including a flange extending beyond the perimeter of said stone, said stone normally extending through said opening, said flange normally contacting the inner marginal portion of said bulge adjacent said opening, a pair of opposed tongues extending from said body portion substantially at points at which said bulge extends from said body portion, said tongues being in a spaced relation with said bulge, and a stiff, arcuate spring member supported by said tongues in a manner permitting removal of said spring member when it is desired to replace said stone assembly, said spring member normally bearing against the inner face of said stone assembly for maintaining the latter and said flange in their normal operative positions.

2. The structure recited in claim 1 wherein said spring member is swingable to and from a position in which its ends are engaged by said tongues.

3. The structure recited in claim 1 wherein one of said tongues is provided with a pair of spaced apart lugs extending toward said bulge and one end of said spring member rests upon said one tongue between said lugs.
